UNITED STATES PATENT OFFICE.

CHARLES A. BELKNAP, OF BROOKLYN, NEW YORK.

ENVELOP FEEDING AND EJECTING MECHANISM FOR PRINTING-MACHINES.

SPECIFICATION forming part of Letters Patent No. 758,044, dated April 26, 1904.

Application filed February 24, 1902. Serial No. 95,328. (No model.)

To all whom it may concern:

Be it known that I, CHARLES A. BELKNAP, a citizen of the United States of America, and a resident of New York, borough of Brooklyn, 5 and State of New York, have invented certain new and useful Improvements in Envelop Feeding and Ejecting Mechanism for Printing - Machines, of which the following is a specification.

10 This invention relates to envelop feeding and ejecting mechanism for printing-machines of the class in which an impression is made through a stencil-card as exemplified by the addressing-machine shown and described in 15 my copending application, Serial No. 87,113, filed December 24, 1901.

The objects of the present invention are to provide simple and effective means for separating and feeding one envelop at a time from 20 a stack, means for taking hold of the separated envelop and placing it in position for imprinting, and quick - acting simple means for ejecting the printed envelop, especially where the invention is applied to an addressing- 25 machine using stencil-cards.

The general objects are to provide an efficient, simple, and substantial mechanism adapted to coöperate at properly-timed intervals with the printing mechanism for feeding 30 the envelops for printing and for ejecting or removing them after printing.

My invention consists of certain features of construction and combinations of parts to be hereinafter described in detail and then 35 claimed.

In the accompanying five sheets of drawings, Figure 1 is a side elevation of a printing-machine in which stencil-cards are used and to which is applied the envelop feeding 40 and ejecting mechanism herein described. Fig. 2 is a side elevation of the same parts as seen when viewed from the opposite side. Fig. 3 is a sectional plan, parts of the printing mechanism removed, showing more clearly 45 the parts of the latter which coöperate with the envelop feeding and ejecting mechanism. Fig. 4 is a plan of the envelop feeding and ejecting mechanism. Fig. 5 is a detail of the ejector or knocker. Fig. 6 is a longitudinal 50 sectional view showing more clearly the co-

operation of the printing and feeding mechanism, the feed being interrupted and the printing taking place. Fig. 7 is a similar section, the printing being interrupted and the feeding taking place. Fig. 8 is a detail of the 55 envelop-pusher, showing how it engages an envelop; and Fig. 9 is a detail of the top envelop-guide.

Referring to the drawings, A indicates the frame of the printing-machine or addressing- 60 machine, B the pivoted or movable stencil-carrier, and C the stencil - cards of suitable construction. The frame is provided with a suitable impression bed or table A'. Cams are employed to drive the parts of the printing-machine from the drive-shaft D. These 65 cams are indicated in dotted lines. Arm B² of the stencil-carrier B is oscillated from its appropriate cam, so as to oscillate the stencil-carrier, which is provided with a bottom plate 70 b', in which a pusher or pushers E are guided for feeding the stencil-cards, such as C, along the side guideways. Pushers E are connected by a link F' with a lever F, which is oscillated from its appropriate cam in such a 75 way that when the stencil-carrier moves downwardly the pusher moves forward to feed a stencil - card from a hopper or supply box, while when the stencil-carrier moves upwardly the pusher moves back. 80

A supply box or hopper H is mounted preferably on brackets G, the same also supporting a collecting box or hopper H'. Hopper H is located above the ingoing end of the stencil-carrier and hopper H' at the outgoing 85 end, so that the cards C in supply-hopper H may be fed along the stencil-carrier and after they have been used for printing delivered to the collecting-hopper H'.

Of the inking and impression rolls I I' inking-roll I has its shaft journaled in the ends of links i², which are pivoted to the lever i³, operated from its appropriate cam, while the shaft of impression-roll I' is journaled in extension-links i⁴ of links i². These rolls are 90 guided in the stencil-carrier in such way that when they are moved to the front end of the stencil - carrier the impression - roll I' lowers to make an imprint through the underlying 95 stencil-card upon the envelop which may be 100

in place upon the platen or impression-bed A'. The inking-roll (see Fig. 1) is rotated by its pinion J' meshing with a fixed rack J, and the impression-roll is rotated from the 5 inking-roll by intermeshing gears k k'. (See Fig. 2.)

The inking mechanism comprises also an ink fountain or reservoir P, (indicated by dotted lines in Fig. 3,) which reservoir is toothed 10 and is intermittently turned by a pawl Q, which is spring-retracted and is caused to take against the teeth by means of a tappet q' on the lever z', which strikes the slide Q', that supports the said pawl. The ink exudes 15 from the ink fountain or reservoir onto the padded lower surface of the same; but this feature and other features of the reservoir are not described, as they do not belong to the present invention, for as far as that is 20 concerned inking-roll I, which takes ink therefrom, may be inked in any other desirable and practical manner.

The stencil-cards are fed along the stencil-carrier toward the envelop-feeding mechanism, and after printing of the envelops the card used is delivered to the collecting hopper or box H' by the upward movement of the stencil-carrier, which forces the card against the catches m', causing them to automatically 25 open and gather up the card.

Only so much of the printing-machine has been described as will enable a clear understanding of the connection of its main parts with the envelop feeding and ejecting mechanism now to be described.

A supporting-plate R is suitably supported in the form of a leaf or shelf that extends out from the front end of the printing-machine and is provided with an envelop-holder, 30 preferably formed by upwardly-projecting rods R', located in slots r and secured from the under side of the plate R by means of thumb-nuts R², which may be used to adjust the size of the holder for various sizes of envelops stacked therein with the flaps downward and located on the side adjacent the printing mechanism. A cross-piece R³, supported by fixed rods R⁴ at such distance above the plate R as to form an opening r', is provided 35 with a vertical guideway for an intermediate guide-piece R⁵ (shown in Fig. 9 in detail) and adjusted up or down for various thicknesses of envelops fed forward by the envelop-pushers. These latter preferably consist of 40 a pair of yielding rearwardly-inclined fingers S, which at their upper ends protrude sufficiently through slots r² in the plate R as that they may engage under and at both ends of the flap of the lower envelop—say Z—of the 45 stack when pushed inwardly. A cross piece or head S' of a lever S², which is pivoted to a hanger S³ on the plate R, supports the envelop-feeding fingers S and may be oscillated 50 so as to reciprocate the fingers S by a link S⁴, which, as seen from Figs. 1 and 3, is provided

with an eccentric-strap S⁵, received by an eccentric S⁶, preferably mounted on the drive-shaft D of the printing-machine. By properly positioning the eccentric S⁶ the movements of the feeding-fingers S are so timed as 55 that the inward pushing motion of the said fingers takes place when the stencil-carrier rises to discharge the used stencil-card. The effective clearance of the feeding-fingers S through the opening r' and the separation of 60 the lower envelop only from the stack are produced by the holding down of the middle portion of the envelop by the guide-piece R⁵, which also enables the ends of the envelops to rise without allowing the fingers to abut 65 against any obstacle, which might be the case if there were no guide-piece and the opening r' were narrower.

Located between the envelop-holder and the platen of the impression-bed (which may be 70 arranged on the plate R) is a pair of feed-rolls T T', that are clothed with yielding or elastic material and are respectively journaled in brackets t t', projecting from opposite sides of the plate R, that has an opening r³ to receive 75 the upper portion of roll T, so that it may cooperate with roll T' to feed forward onto the platen or impression-bed the envelop delivered to it by the feeding-fingers S. Gears t² t³ are arranged on the shafts of rolls T T' and 80 mesh to cause the rolls to revolve oppositely, to which end the gear t² is meshed by a driving-gear t⁴, fixed on a shaft t⁵, journaled in bearings t⁶, and carrying also a sprocket-wheel U, over which runs an endless sprocket-chain 85 U', that also runs over a large drive sprocket-wheel U², that is fixed preferably on the cam-shaft D of the printing-machine. As shown, the feed-rolls rotate constantly, and when the feeding-fingers S separate and push the lower 90 envelop Z out between the rolls the rolls grip the envelop, feed it toward, and deliver it onto the platen or impression-bed A' at a time when the stencil-carrier is raised. Thus the envelops are fed oppositely to the stencil-cards, both 95 being fed to a common point over the platen or impression-bed. A suitable stop limits the amount of inward feed of the envelop, and this stop is automatically depressed by the stencil-carrier for moving it out of the way. Said 100 stop consists of an upwardly-projecting transverse lip V, located behind the platen or impression-bed A' and preferably formed by bending it up at right angles to a spring-plate V', the shape of which can be more clearly 105 seen from Fig. 4 and which is adjustable by means of its clamping-screw V², which enters plate R. Additional support for the spring-plate V' is afforded by extending it over the 110 shaft of the lower feed-roll. The adjustability 115 of the spring-plate and stop provides for defining the extent of inward movement of various widths of envelops. After the impression has been printed on the envelop by the inked 120 impression-roll I' and when the stencil-carrier 125

is rising to discharge the used stencil-card a knocker strikes one end of the printed envelop and ejects it from the side of printing-machine into a suitable receptacle, as shown in Fig. 4, 5 or into the hands of the attendant at the machine. The knocker consists, preferably, of a shank W^1 , provided with a foot W , guided on the plate R and located beyond one end of the platen or impression-bed A' . A set-screw W^2 passes through a slot in shank W' and into the end portion of a spring-actuated arm W^3 , pivoted to the plate R . An actuating-spring W^4 is adapted to quickly throw the knocker and arm from the dotted to the full line position of Fig. 4, so that the knocker 15 will forcibly eject the printed envelop. The spring W^4 is placed under tension due to the action of an end cam X on a projection W^5 of the arm W^3 . Said cam X is mounted at 20 the side of the feeding mechanism on a shaft X' , preferably journaled in suitable bearings of the frame A and rotated by a sprocket-chain X^2 , which runs over a sprocket-wheel X^3 on cam-shaft D and another sprocket-wheel 25 X^4 on the shaft X' . The incline y on the cam bears upon the projection W^5 and gradually places the spring W^4 under tension, and then when the projection passes the high point of the incline the spring suddenly acts on the 30 arm W^3 and throws the knocker against the printed envelop. The development of the cam-surface is such that at the proper moment, after the stencil-carrier has raised sufficiently, the spring force is released.

35 As far as the broad idea is concerned it is evident that there is originality in feeding stencil-cards and articles, such as envelops or sheets, on which an impression is to be made through the stencil-cards to a common 40 point and then discharging the articles printed sidewise of the line of feed.

It will be apparent to skilled mechanics that various alterations can be made in the details without departing from the scope and 45 spirit of the invention.

What I claim as new and of my invention is—

50 1. The combination of a platen or impression-bed, means for feeding stencil-cards thereto, means for feeding the articles to receive the imprint, to the platen, said feeding means being arranged at opposite sides of the platen and feeding toward the platen as a common point, means for impressing the stencil onto the articles, and means for moving the used stencil-cards directly away from the platen, transversely to the direction of the feed of the cards and the articles, substantially as described.

55 2. The combination of a platen or impres-

sion - bed, means for feeding stencil - cards thereto, means for feeding the articles to receive the imprint to the platen or impression-bed, means for impressing the stencil onto the articles, means for removing the stencil-cards 65 from the printed articles, and means for removing the printed articles sidewise of the line of feed of the card-feeding means, substantially as described.

3. The combination of a platen or impression - bed, means for feeding stencil - cards thereto, means for separating and feeding from a stack the articles to receive the imprint to the platen or impression-bed, means for impressing the stencil onto the articles, 75 and means for knocking the printed articles to one side of the line of the card - feeding means, substantially as described.

4. The combination, in an envelop-feeding mechanism, of means for separating and feeding envelops from a stack, feed-rolls for taking up the fed envelop, a platen onto which the envelop is fed, and means located near one end of the feed-rolls for ejecting the envelop laterally from the platen, substantially as de- 85 scribed.

5. The combination of means for feeding envelops to a platen or impression - bed, a spring-actuated pivoted arm, a knocker located on and at angle to one end of the arm to 90 one side of the line of feed, and means for straining the spring and to release the arm and knocker, substantially as set forth.

6. The combination, with a platen or impression-bed, and a stencil-card carrier, one of said parts being movable relatively to the other, of a spring-stop for the article to be printed acting when the movable part is moved away from the other to intercept the article and the movable part automatically retracting the stop 100 when the cards are being fed, substantially as described.

7. The combination of a platen or impression-bed, timed means for feeding stencil-cards thereto, means for producing the impression 105 through the stencil-cards, means for feeding the articles to be printed, to the platen, a suitably-driven cam timed relatively to the card-feeding means and the article-feeding means, and a knocker suitably actuated from said cam 110 to discharge the printed article sidewise relatively to the line of feed, substantially as described.

Signed at New York, N. Y., this 19th day of February, 1902.

CHARLES A. BELKNAP.
